CHILD'S TOILET SEAT

Fred O. Forsman, Thousand Oaks, and George Mc-Cutcheon, Los Angeles, Calif., assignors to Westland Plastics, Inc., Newbury Park, Calif., a corporation of California

Filed Nov. 17, 1964, Ser. No. 82,646

Term of patent 14 years

(Cl. D4—5)

FIG. 1 is an isometric view of the child's toilet seat of our design:

FIG. 2 is a rear isometric view;
FIG. 3 is a front elevational view;
FIG. 4 is a top plan view;
FIG. 5 is a side elevational view;
FIG. 6 is a rear elevational view; and
FIG. 7 is a bottom plan view.

The strap, shown in broken lines in FIGS. 1, 4 and 5, is included for illustrative purposes only.

We claim:

The ornamental design for a child's toilet seat, as shown and described.
